PRACTICE PUTTING TARGET

Harold W. Scholin, 1125 N. Northwest Highway,
Park Ridge, Ill. 60068

Filed Apr. 1, 1966, Ser. No. 1,743

Term of patent 14 years

(Cl. D34—5)

FIG. 1 is a perspective view of a practice putting target embodying my new design;

FIG. 2 is a front elevational view thereof;

FIG. 3 is top plan view thereof;

FIG. 4 is a side elevational view thereof;

FIG. 5 is a rear elevational view thereof; and

FIG. 6 is a bottom plan view thereof on a reduced scale.

The two sides of the practice putting target are symmetrical. The essential features of the design reside in the portions shown in full lines.

I claim:

The ornamental design for a practice putting target, as shown and described.
